UNITED STATES PATENT OFFICE.

OSCAR ALFRED NENNINGER, OF EL PASO, TEXAS.

WATER-STILL.

No. 842,687.

Specification of Letters Patent.

Patented Jan. 29, 1907.

Application filed May 2, 1906. Serial No. 314,780.

To all whom it may concern:

Be it known that I, OSCAR ALFRED NENNINGER, a citizen of the United States, and a resident of El Paso, in the county of El Paso 5 and State of Texas, have invented certain new and useful Improvements in Water-Stills, of which the following is a specification.

My invention is an improvement in water-stills, and consists in certain novel constructions and combinations of parts hereinafter described and claimed.

Referring to the drawings forming a part hereof, Figure 1 is a side elevation of my improved still. Fig. 2 is a longitudinal vertical section thereof, and Fig. 3 is a plan view of the distilled-water-receiving pan; and Fig. 4 is a detail sectional view of the upper part of Fig. 2, showing the connection between the main and the condensing cylinder.

In the present embodiment of my invention I provide a stand A, comprising a base a and a yoke a', whose arms a' a'' support the boiler-pan B. The boiler-pan is preferably 25 constructed of cast-iron glazed inside or any other suitable material not easily affected by moisture and is connected to the water-back or circulating-pipes of a kitchen-range or any kind of heating medium in which water-circulation pipes may be placed by means of 30 pipes b and b'', the pipe b leading to the water-back and the pipe b'' therefrom. In order to avoid confusion, the pipe b will be hereafter designated as the "discharge-pipe" and 35 the pipe b'' as the "steam-supply pipe."

The discharge-pipe b is arranged beneath the boiler-pan and extends to the opposite side thereof, a T-joint b' being interposed in the length thereof and having its vertical 40 member connected by a pipe b' with approximately the center of the boiler-pan. A second T-joint b'' is arranged upon the end of of the discharge-pipe b, having a faucet b' connected with its horizontal member and a pipe b'' connected with its vertical member, the 45 said pipe b'' extending upwardly alongside the still for a purpose to be hereinafter described.

A water-gage b' is arranged alongside the 50 pipe b'', near the lower end thereof and communicates at either end therewith, the upper end of the water-gage being provided with a faucet b''. An overflow-pipe b' is arranged within the boiler-pan, the said pipe having 55 its opening at the level at which it is desired to maintain the water in the boiler-pan, and

a trap b' is interposed in the length of the overflow-pipe.

The steam-supply pipe b' communicates with the boiler-pan at a higher level than the 60 discharge-pipe and is provided with a T-joint communicating by an elbow b'' with the source of the steam-supply, as shown in Fig. 2, giving admission to a small air-pipe b', arranged within the supply-pipe and extending to the inner end thereof.

A flange b' is provided on the upper edge of the boiler-pan to form a seat for the distilled-water-receiving pan C, the pan being provided with a discharge-faucet c' and with 70 a plurality of vertical tubes c, extending therethrough and forming communicating passages between the boiler-pan and the space above the distilled-water-collecting pan. A jacket D is arranged above the distilled-water-collecting pan, resting upon flanges c', formed in the upper edge of the 75 said pan, the jacket forming a condensing-chamber above the distilled-water-collecting pan.

The condensing-cylinder E is supported 80 within the condensing-chamber by means of the flanges E' thereon, and the upper end of the cylinder is provided with a cross-joint e, having extending vertically therethrough a 85 supply-pipe e', connected with a water-main or other source of water-supply, the admission of the water to the condensing-cylinder being controlled by a valve e'', interposed between the supply-pipe and the water-main. 90

The supply-pipe e' extends almost to the bottom of the condensing-cylinder, and to the lateral branches of the cross-joint are connected a discharge-pipe e'', closed by a faucet e', and a pipe e'', extending downwardly alongside the condensing-chamber to the pipe b'', before mentioned, with which it 95 communicates.

A valve e''' is interposed in the length of the pipe e'', and connected to the said pipe 100 just above the valve e'' is a pipe f, the said pipe f opening into the bottom of the boiler-pan.

The admission of the water to the boiler-pan through the pipe f is regulated by means 105 of a valve b' in the said pipe f, the valve being connected to a float b'' by a flexible connection in such manner that when the water in the boiler-pan reaches a predetermined level the valve is closed, shutting off the water-supply. Adjacent to the upper edge of the 110 condensing-chamber D is a small opening d'

for relieving excess pressure in the said chamber.

In operation the steam passes into the boiler-pan through the pipe b^6 and thence passes upwardly through the openings c into the condensing-chamber and into contact with the cold outer surface of the condensing-cylinder. The said steam being condensed flows back into the distilled-water-receiving pan, where it may be drawn off for use through the faucet c' . The circulation of water in the boiler-pan is maintained through the pipes b b^6 , and sufficient air to aerate the distilled water is admitted through the pipe b^7 , the steam acting as an injector to draw the air into the chamber. The water in the condensing-cylinder as it becomes heated by the heat from the condensed steam may be drawn off through the faucet e^6 for domestic uses. A constant supply of warm water is supplied to the boiler-pan from the condensing-cylinder through the pipes e^3 and f . It will be understood that when the hot water is to be drawn off from the condensing-cylinder through the faucet e^6 the valve e^2 is opened and the cold water from the main forces out the hot water through the said faucet. The valve e^2 is likewise opened when warm water is to be passed from the condenser-cylinder to the boiler-pan. By interposing the trap b^{10} within the overflow-pipe I provide against the entrance of foul air into the condensing-chamber and against the escape of steam therefrom.

The condensing-chamber may consist of the ordinary house-boiler, if desired, or may be made especially for the still. By connecting my improved still as described the house-boiler is made to serve a double purpose—that of a condensing-chamber and that of a hot-water receptacle.

My improvement is easily installed and with but little expense.

I claim—

1. In a water-still, the combination of a base, a boiler-pan supported on the base and provided with inlet and outlet pipes, adapted to be connected with a source of boiling water, the inlet-pipe being arranged at a higher level than the outlet-pipe, an air-supply pipe within the inlet-pipe, a condensing-chamber above the boiler-pan and provided with a vent in its upper end, a condensing-cylinder within the chamber, a pipe for connecting the condensing-cylinder with a source of

water-supply, a pipe connecting the source of water-supply with the boiler-pan, a float-valve within the boiler-pan at the opening of the said pipe, a receiving-pan below the condenser and between the condensing-chamber and the boiler-pan, a plurality of tubes connecting the boiler-pan with the condenser and traversing the receiving-pan, an outlet-pipe for the receiving-pan, an overflow-pipe connected with the boiler-pan, and a trap interposed in the overflow-pipe.

2. In a water-still and in combination, a boiler-pan, supply and discharge pipes for connecting the boiler-pan with a water-back, an air-supply pipe within the supply-pipe, a condensing-chamber above the boiler-pan, a condensing - cylinder within the chamber, means whereby the cylinder may be connected with a source of water-supply, means below the chamber for receiving the distilled water, and means for connecting the boiler-pan with the source of water-supply.

3. In a water-still and in combination, a boiler-pan, a supply and discharge pipe for connecting the pan with a water-back, an air-pipe within the supply-pipe, a condensing-chamber above the boiler-pan, a receiving-pan within the boiler-pan and the condensing-chamber, tubes forming a communication between the boiler-pan and the condensing-chamber, a condensing-cylinder within the chamber, and means whereby to connect the condensing-cylinder with a source of cold-water supply.

4. In a water-still and in combination, a pan for receiving heated water, supply and discharge pipes for the pan, an air-pipe within the supply-pipe, a condensing-chamber supported above the pan, a receiving-pan below the condensing-chamber, and a condensing-cylinder supported within the chamber above the receiving-pan.

5. In a water-still and in combination, a boiler-pan for receiving heated water, means whereby the heated water may circulate to and from the pan, an air-pipe traversing said means and communicating with the pan, a condensing-chamber above the pan, a condensing-cylinder within the chamber, and a receiving-pan between the chamber and the boiler-pan.

OSCAR ALFRED NENNINGER.
